UNITED STATES PATENT OFFICE

OSCAR BREITHAUPT, OF DETROIT, MICHIGAN

NAIL HOLDER

Application filed August 10, 1928. Serial No. 298,661.

My invention relates to a new and useful improvement in a nail holder, and has for its object a provision of a nail holder whereby a parallelity of nails may be deposited in a conveying trough and permitted to slide to one end thereof from which they may be removed by a magnetic hammer, and in order to prevent the removal of more than a single nail at a time by the hammer, a magnet is located adjacent to the end of the trough.

Another object of the invention is the provision of a magnetic means for magnetizing the nails moving to the end of the nail holder.

15 Another object will appear hereinafter.

The invention consists of a combination and arrangement of parts hereinafter described and claimed.

The invention will best be understood by 20 the reference to the accompanying drawings, which form a part of this specification and in which,

Fig. 1 is a side elevation view of the invention.

25 Fig. 2 is a front elevation view of the invention.

Fig. 3 is a fragmentary sectional view taken on line 3—3 of Fig. 2.

The invention comprises a container, having a chute 8 leading therefrom to deposit the nails in a trough comprising the side members, 9 and 10, which are spaced apart. A sorting arm, 11, is mounted to engage in the trough and arrange the nails, 12, as they 35 pass thereby, so that they will project downwardly in the space between the side members, 9 and 10, the heads of the nails preventing their falling through the trough. Mounted in the outlet end of the trough is a 40 shield comprising side walls, 13 and 14, and a base, 15, all formed preferably from a single piece of material. The front wall, 16 is flared outwardly and turned as at 17, to provide a retainer in which the nails may be 45 deposited when supplying off the forward end of the trough. Mounted between the side walls, 13 and 14, is a magnet 18 with the magnetized end adjacent the container 17.

In operation, the device is carried on the 50 cap, or the head of the user and the trough

inclined forwardly. The present invention is designed particularly to afford a holder from which the nails may be removed by a magnetic hammer.

The use of the magnet is necessary in order to prevent the magnetic hammer from removing more than a single nail from the container, 17, at a time. The operation of the magnet, 18, on the nails has proven most efficient in preventing the removal by the 55 magnetic hammer of more than a nail, thus making a nail holder of this class practicable for use with a magnetic hammer.

While I have illustrated and described the preferred form of construction, I do not 60 wish to limit myself to the precise detail of structure shown, but desire to avail myself of such variations and modifications as come within the scope of the appended claims.

Having thus described my invention what 70 I claim as new and desire to secure by Letters Patent is:

1. In a nail holder of the class described: a nail container; a nail receiving trough positioned beneath said container for receiving 75 nails dropping from said container, said trough having a longitudinally extending slot formed therein; a container mounted on and positioned adjacent the forward end of said trough and below the same for reception of nails from said trough; and a magnet positioned in said second mentioned container.

2. A nail holder of the class described, comprising: a nail container; a trough positioned below said nail container adapted for reception of nails passing from said container, said trough having a longitudinally extending slot formed in its base; a nail receptacle mounted on the forward end of said trough and positioned beneath the same for reception of nails passing from said trough; and a magnet positioned in the lower end of said second mentioned container and fixed toward the front thereof for arranging the nails passing from said trough.

In testimony whereof I have signed the foregoing specification.
